Specification for Design.

Patented Dec. 14, 1920.

Application filed June 30, 1920. Serial No. 393,181. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for a Socket-Cover for a Lighting-Fixture, of which the following is a specification, ref-

erence being had to the accompanying drawing, forming part thereof.

The single figure of the drawing is a perspective view of a socket cover for a lighting fixture, showing our new design.

We claim:

The ornamental design for a socket cover for a lighting fixture, as shown.

GEORGE V. STRAHAN.
FREDERICK W. MATHIEU.
